UNITED STATES PATENT OFFICE.

BENJAMIN PERRY, OF CLEVELAND, OHIO.

FURNACE.

1,248,703.

Specification of Letters Patent. Patented Dec. 4, 1917.

Application filed March 10, 1917. Serial No. 154,013.

To all whom it may concern:

Be it known that I, BENJAMIN PERRY, a citizen of the United States, resident of Cleveland, county of Cuyahoga, and State of Ohio, have invented new and useful Improvements in Furnaces, of which the following is a specification, the principle of the invention being herein explained and the best mode in which I have contemplated applying that principle, so as to distinguish it from other inventions.

My invention relates to furnaces and particularly to that class of such structures as use coke gas, coal gas, etc., or in season natural gas, mixed with air to form the combustible heating mixture. It is the object of my invention to so dispose the natural gas burners relatively to the furnace structure that the heat therefrom will not deleteriously affect the roof of the furnace after the brick arch between the artificial gas port and the air ports has been burned away, and yet preserve the maximum heating or cutting effect before said arch is burned away, 25 as hereinafter fully described.

The annexed drawings and the following description set forth in detail certain means embodying my invention, the disclosed means, however, constituting but one of various mechanical forms in which the principle of the invention may be employed.

In said annexed drawings:—

Figure 1 represents a vertical longitudinal section of my improved furnace, the 35 left-hand end thereof being taken in a plane through an artificial gas port 2 and the right-hand end thereof being taken in a plane through an air port 3; Fig. 2 represents a longitudinal section of a fragmentary portion of such furnace, showing the brick arch partially burned away and also illustrating a modified form of structure in which the arrangement of the natural gas burner is somewhat different from that illustrated in Fig. 1; and Fig. 3 represents a vertical transverse section taken in the plane indicated by the lines 3—3, Fig. 1.

I have illustrated in the drawings a furnace with the usual main structure 1 and 50 roof 1'. Said furnace is a reversible one in that the direction of movement of the heating gases may be from left to right or vice versa, and to this end when the movement of said gases is from left to right, I show 55 a central gas port 2 upon the left-hand of

Fig. 1 and two outer air ports 3, said gas and air ports being separated in the end of the main structure 1 by suitable partitions and in the top part of the structure by the brick arch 4 and converging to merge one with the other at the point 5 which is the normal mixing point of the gas and air, is being presumed that coke gas, coal gas or other gas derived from other operations is being used. The mixing point 5, as will be 65 plainly noted in the drawing, is the outer end of the combined mixing, combustion and heating chamber of the furnace. Said ports 2 and 3 comprise substantially vertical portions and portions inclined somewhat from 70 the horizontal, which inclined portions converge at the mixing point 5, as before mentioned. Said dividing arch 4 is disposed in planes somewhat inclined from the horizontal, as plainly shown in the drawing. 75 The burning gases pass through the structure and out through the two ports 3 and the port 2, in the right-hand end of the structure, to the stack. When the direction of movement of the heating gases is from 80 right to left, the right-hand port 2 is a gas inlet and the two right-hand ports 3 are air inlets, and the three ports at the left-hand end of the structure are exhaust ports for the consumed gases.

85 All that has been heretofore described, in so far as it relates to a reversible furnace using producer gas, is well-known and I shall now describe in relation thereto the use and disposition of natural gas burners 90 to be used in season when coke gas, coal gas and analogous fuel is not available.

The brick arches 4 are burned away in time under the use of artificial gas and greatly deteriorated so that they expose the 95 roof 1' of the furnace structure to burning gases which are swept up through the deteriorated arch by the upward movement of the air through the port 2, when the conditions are such that the natural gas burner 6 is utilized, the same being in the position in which burner 6 is shown in Fig. 1. Also, the burning gases are swept so far away from the steel to be cut that they cannot be adequately controlled. To obviate this deterioration of the roof 1' and to properly control the gases, I have provided the general main supply pipe 10 of natural gas with two branches 7 and 9, branch 7 leading to burner 6 and branch 9 leading to a burner 8, as 100 110

plainly shown in Fig. 1. Now, when the brick arches 4 have deteriorated so that burning gases would be swept therethrough to the damage of the roof 1', I shut off the branch pipe 7 by means of cock 7' and utilize branch pipe 9, it also having a suitable cock 9'. It will be noticed that the burner 8 thus utilized is disposed adjacently to the inner end of the arch 4 so that the sweep of the air through that part of the passage 2 which is adjacent to said burner 8, being in a generally horizontal direction, if not positively downwardly, as shown in Fig. 1, as also the sweeping and blanketing effect of the air through passages 3 above the arch 4, will cause the heating gases to be carried longitudinally through the furnace structure and through the steel to be cut and not against the roof.

In Fig. 2 I have illustrated a modified form of structure for thus protecting the roof 1' in that, instead of using, before the brick arches 4 are burned away, a natural gas burner in the position shown for burner 6, I use burner 8 disposed adjacently to the inner end of the brick arch 4 all the time, so that it is not necessary to change from one natural gas burner to another, after the said arches have been burned away. The form of structure shown in Fig. 1, however, is preferable inasmuch as the location therein shown of the burner 6 furnishes a sharper flame which will cut the metal more efficiently than will the burner located at the point 8, the burner 6 being farther from the center of the furnace and providing a better mixture than when the burner is located at the point 8. I have ascertained, however, that on the whole it is better to suffer such disadvantage as accrues from the location of the burner 8, when the arch 4 is burned away, rather than to shut down the furnace immediately and repair the arch, or to have the roof 1' deteriorated by using the burner at the position 6.

It should be noted, of course, that when the natural gas burners are used, all of the ports 2 and 3 are open, *i. e.*, they are air ports. Further, when it is desired to change from natural gas back to coke gas, coal gas or similar heating medium, for any reason, because of the proper season, etc., the furnace is shut down, if the brick arches 4 are deteriorated to such a point that there is left no nose on the arch projecting beyond the vertical plane of the inner wall of the passage 2 and said arches rebuilt before the furnaces are utilized with said artificial gas. The arch 4, shown in Fig. 2 as quite largely burned away, has not been burned to a point where it cannot be utilized with regenerated gas, inasmuch as there is still left to the arch a nose projecting beyond the vertical plane containing the inner wall of the gas passage 2. A slight further deterioration of said

arch would, however, destroy said nose so as to necessitate the rebuilding of the arch.

What I claim is:

1. In furnaces, the combination with a main body structure formed with gas and air passages, and a mixing, combustion and heating chamber, said passages comprising vertically disposed portions and portions inclined somewhat from the horizontal, the latter portions communicating at their inner ends with said chamber; of an auxiliary gas supply passage communicating with the interior of said main body structure adjacently to the outer end of said chamber, and means for controlling the flow of gas through said last-named passage.

2. In furnaces, the combination of a main body structure formed with a vertically disposed end partition and a dividing arch inclined somewhat from the horizontal, said partition and arch creating air and gas passages comprising vertically disposed and inclined portions; a mixing, combustion and heating chamber communicating with said inclined portions of said passages; an auxiliary gas supply passage communicating with the interior of said main body structure adjacently to the inner end of said arch; and means for controlling the flow of gas through said last-named passage.

3. In furnaces, the combination of a main body structure; gas and air passages and a mixing chamber therein; an auxiliary gas supply passage, said latter passage branching and communicating with the interior of said main body structure at a plurality of points; and means for independently controlling the flow of gas through the several branches of said auxiliary passage.

4. In furnaces, the combination of a main body structure, gas and air passages and a mixing chamber therein; an auxiliary gas supply passage, said latter passage branching and intersecting said first-named gas passage at a plurality of points; and means for independently controlling the flow of gas through the several branches of said auxiliary passage.

5. In furnaces, the combination of a main body structure; gas and air passages and a mixing chamber therein; an auxiliary gas supply passage, such latter passage branching and communicating with the interior of said main body structure at a plurality of points, one of said points being adjacent to said mixing chamber; and means for independently controlling the flow of gas through the several branches of said auxiliary passage.

6. In furnaces, the combination of a main body structure, gas and air passages and a mixing chamber therein; an auxiliary gas supply passage, said latter passage branching and intersecting said first-named gas passage at a plurality of points, one of said

points being adjacent to said mixing chamber; and means for independently controlling the flow of gas through the several branches of said auxiliary passage.

7. In furnaces, the combination with a main body structure formed with a dividing arch and gas and air passages separated for some distance from each other by said arch, said gas and air passages converging adjacently to the inner end of said arch; of an auxiliary gas supply passage communicating with the interior of said main body structure adjacently to the inner end of said arch, and means for controlling the flow of gas through said auxiliary passage.

8. In furnaces, the combination with a main body structure formed at either end with a dividing arch disposed at an inclination somewhat from the horizontal and gas and air passages separated for some distance from each other by said arches, said gas and air passages converging adjacently to the inner end of said arches; of auxiliary gas supply passages intersecting said first-named gas passages, and means for controlling the flow of gas through said auxiliary passages.

9. In furnaces, the combination with a main body structure formed at either end with a dividing arch and gas and air passages separated for some distance from each other by said arches, said gas and air passages merging adjacently to the inner ends of said arches; of auxiliary gas supply passages intersecting said first-named gas pas-

sages adjacently to said inner ends of said arches respectively, and means for controlling the flow of gas through said auxiliary passages.

10. In furnaces, the combination of a main body structure formed at either end with a dividing arch and gas and air passages separated for some distance from each other by said arches, said gas and air passages merging adjacently to the inner ends of said arches; auxiliary gas supply passages, said latter passages each branching and intersecting said first-named gas passages, respectively, at a plurality of points; and means for independently controlling the flow of gas through the several branches of each of said auxiliary passages.

11. In furnaces, the combination of a main body structure formed at either end with a dividing arch and gas and air passages separated for some distance from each other by said arches, said gas and air passages merging adjacently to the inner ends of said arches; auxiliary gas supply passages, said latter passages each branching and intersecting said first-named gas passages, respectively, at two points, one of said points being adjacent to said inner ends of said arches; and means for independently controlling the flow of gas through the two branches of each of said auxiliary passages.

Signed by me, this 24th day of February, 1917.

BENJAMIN PERRY.
